ANDRÉ VARAUD, OF GENEVA, SWITZERLAND

FUSE FOR ARTILLERY PROJECTILES

Application filed January 29, 1930, Serial No. 424,167, and in Switzerland January 30, 1929.

With fuses for artillery projectiles and particularly multiple action fuses, it is necessary to employ an exterior member situated in the nose of the fuse so as to allow easy regulation of the effect desired. In certain of these fuses of the percussion type with delayed action, use is made of exterior means, located radially of the nose of the fuse, for regulating the action, but in this case it is necessary to have the centrifugal member and the locking member placed in the same plane.

This results in a very long and unwieldy construction of the fuse body, this being a great disadvantage particularly for small calibre projectiles whose equilibrium is thus affected and whose explosive capacity is greatly reduced.

The object of the present invention is to construct an improved multiple action projectile fuse having a centrifugal member for controlling one of the fuse actions, the controlling arrangement being characterized by the fact that the member situated in the nose of the fuse and located radially of the projectile axis is provided with an eccentric portion which co-operates with a plunger movable in a direction substantially parallel to the axis of the projectile and which has a free end of appropriate length to contact with and lock the centrifugal controlling member when the eccentric is turned correctly.

The annexed drawings show by way of example two different forms of the arrangement according to the invention, one being applied to a percussion fuse with instantaneous and retarded action and the other to a mechanical fuse operating after a certain time or on percussion.

Fig. 1 is an elevation partly in section of a projectile fuse with instantaneous or delayed action with the arrangement according to the invention in inoperative position, the eccentric portion being turned towards the top of the fuse.

Fig. 2 is a partial view of the nose of the fuse showing in elevation the radial control member turned into the desired position to obtain instantaneous action.

Fig. 3 is a view similar to Fig. 1 in which

the fuse control is in the operative position, the eccentric portion being turned downwardly.

Fig. 4 is a detail view similar to Fig. 2 in which the radial control member is in the reverse position to give a retarded action.

Fig. 5 shows in section and in partial elevation the control arrangement of the invention applied to a double acting mechanical fuse.

Fig. 6 is a detail view of the control member in the body of the fuse regulated to obtain operation on percussion.

Fig. 7 shows in section and partial elevation the arrangement according to the invention in its operative position as applied to a fuse of the type shown in Fig. 5, set for seven seconds.

Fig. 8 is a view similar to Fig. 6 in which the radial control member is regulated to obtain a timed action.

Referring to the drawings, Figs. 1 to 4, it will be seen that the arrangements comprise the following main parts:

A key 2, a screw 3, a vertical plunger 4, a spring 5 and a guide sleeve 6. The key 2 has a head 2a of a larger diameter and an eccentric portion 2b. It is also provided with a slot 2c, a mark 2d, and a conical groove 2e. This key 2 is placed radially within the nose of the fuse and is held in place by a screw 3. The latter has a conical end 3a which co-operates with one of the sides of the conical groove 2e in the key 2 in such a manner as to allow regulation of the friction of the key 2 and its housing.

The eccentric portion 2b co-operates with the head of plunger 4 subjected to the action of a helical spring 5 which bears between the head of said plunger and the top of the guide sleeve 6 for the stem of plunger 4. The free end of this plunger 4 co-operates with the external part of a centrifugal bolt 7 which, as shown, is rigid with an obturating member controlling the firing passage 8 of the primer 9 leading to the detonator 10 of the fuse.

The operation of the arrangement is as follows:—

If the mark 2d on the key 2 is turned to

register with the zero mark $1a$ on the nose of the fuse body, Figure 2, this will indicate that the fuse is to function instantaneously. In this position the eccentric portion $2b$ is turned upwardly in the fuse to allow the plunger 4 to rise under the action of its spring 5 and to liberate the centrifugal bolt 7 (Fig. 1). The latter, during the trajectory, moves out under the action of centrifugal force against the action of its spring $7a$ and opens the communicating passage for the primer 9 ready for its ignition on impact. On the other hand, if the mark $2d$ of the key is reversed so as to register with the letter R at $1b$, Fig. 4, the eccentric $2b$ of the key will be turned down as shown in Fig. 3, and the free end of the plunger descends into a notch $7b$ in the bolt 7 to hold the latter in the position shown in Fig. 3. The bolt 7 cannot then move out under the action of centrifugal force during the flight of the projectile and, on impact, the flame of the primer cannot pass through the ignition passage due to a metal plate $7c$ which is connected to the bolt 7 and closes the said passage in known manner. The primer thus ignites the retard charge 11 and the detonator is operated after a certain length of time.

Figs. 6 to 8 show the arrangement applied to a double acting mechanical fuse operating either after a certain period of time controlled by the fuse clockwork or by percussion due to inertia effects. In this type of fuse one of these operations only is required on occasions while the other is prevented. If a fuse of this type is timed before firing to obtain operation during the flight, it is very useful to prevent bursting of the projectile on hitting the ground if the timing mechanism of the fuse does not function during the flight of the shell. This function is performed by the arrangement according to the invention in this type of fuse.

In Figure 5 it will be seen that the radial member 2 is in the inoperative position, the eccentric portion $2b$ being turned upwardly whilst the pin 4 has liberated one of the centrifugal bolts 7 under the action of the spring 5 . In this position the fuse can be fixed as a double-acting time fuse, that is to say, if the timed operation has not occurred during the flight, the inertia percussion mechanism 12 functions on impact.

In Fig. 8, $1c$ and $1d$ represent indications (P and T) for percussive and timed operation respectively, $2c$ being the slot with which the controlling member 2 is turned and $2d$ the mark carried thereby. Figs. 7 and 8 show the control arrangement in the actual position regulated for time operation of the fuse. The eccentric portion $2b$ of the member 2 is turned downwardly so that with the pin 4 descending the centrifugal bolt 7 is locked and cannot move from its position for locking the plug 12 as shown in Fig. 7.

The fuse shown by way of example at 7" can only operate during the trajectory by the action of the clockwork. As shown in Fig. 8 the mark $2d$ of the member 2 is in register with the mark $1d$ or letter T. 70

As will be seen the invention consists in a control arrangement with an eccentric part which may be used in all types of fuse to lock a centrifugal bolt in a given position against the action of the centrifugal force arising 75 during the flight of the projectile.

What I claim is:—

1. In a fuse, controlling mechanism comprising a centrifugal control bolt, an axially disposed plunger adapted to be set to prevent movement of said bolt, a spring for loading said plunger, and an exteriorly operable setting spindle having an eccentric portion 80 capable of engaging said plunger.

2. In a fuse, controlling mechanism comprising a centrifugal control bolt, an axially disposed plunger bolt adapted to be set to prevent movement of said bolt, and an exteriorly operable setting spindle having an eccentric portion capable of engaging said 85 plunger. 90

3. In a fuse, controlling mechanism comprising a centrifugal control bolt, an axially disposed plunger bolt adapted to be set to prevent movement of the said bolt, and an exteriorly operable setting spindle having an eccentric portion capable of engaging said 95 plunger, said plunger bolt being assisted by a spring. 100

4. In a fuse, controlling mechanism comprising a centrifugal control bolt, an axially disposed plunger bolt adapted to be set to prevent movement of the said bolt, and an exteriorly operable setting spindle having an eccentric portion capable of engaging said 105 plunger, a helicoidal spring adapted to bear between the head of said plunger and the top of a guide sleeve for the stem of the plunger.

In testimony whereof I have affixed my signature. 110

ANDRÉ VARAUD.
